(57) CLAIM

We claim the ornamental design for a heart-shaped bagel with snack container insert, as shown and described.

DESCRIPTION

FIG. 1 is a top perspective view of the heart-shaped bagel with snack container insert.

FIG. 2 is a top plan view thereof.

FIG. 3 is a bottom plan view thereof.

FIG. 4 is a top perspective view of the snack container only shown separately for clarity.

FIG. 5 is a bottom plan view of FIG. 4.

FIG. 6 is a top plan view of FIG. 4.

FIG. 7 is a front elevational view of FIG. 4.

FIG. 8 is a side elevational view of FIG. 4; and, FIG. 9 is a rear elevational view of FIG. 4.
